CLAIM

The ornamental design for a water closet lid, as shown and described.

DESCRIPTION

In a preferred embodiment, the nature of this product is as a plumbing fixture in the form of a water closet lid.

FIG. 1 is a right, top, front perspective view of a water closet lid embodying my new design;

FIG. 2 is a top plan view thereof;

FIG. 3 is a front elevational view thereof;

FIG. 4 is a left side elevational view thereof, the right side elevational view thereof being a mirror image of the left side shown;

FIG. 5 is a rear elevational view thereof; and,

FIG. 6 is a bottom plan view thereof.

The broken line representations of underside features in FIGS. 3-6 are for the purpose of illustration only, and form no part of the claimed design.
